UNITED STATES PATENT OFFICE.

DANIEL W. SIMMONS, OF ROME, GEORGIA.

DESIGN FOR A BOWL OR TUREEN.

44,595.

Specification for Design.

Patented Aug. 26, 1913.

Application filed June 28, 1913. Serial No. 776,443. Term of patent 14 years.

To all whom it may concern:

Be it known that I, DANIEL W. SIMMONS, a citizen of the United States, residing at Rome, in the county of Floyd and State of Georgia, have invented a new, original, and ornamental Design for a Bowl or Tureen, of which the following is a specification, reference being had to the accompanying drawing, forming a part thereof.

Figure 1 is a side view of the bowl or

tureen, showing my new design and, Fig. 2 is an end view of the same.

I claim:

The ornamental design for a bowl, or tureen, as shown.

DANIEL W. SIMMONS.

Witnesses:

W. J. SATTERFIELD,

P. I. MORRIS.
